ABSTRACT

A torque spanner comprises: a body having a tubular passageway therethrough; a first lever pivoted within the passageway intermediate its ends, one of its ends projecting from the passageway which end is arranged to apply torque or carry torque applying means of which the torque reaction tends to rotate the lever about its pivot; a bell-crank lever within the passageway, one arm of the bell-crank lever being pivotally connected to the other arm of the first lever, the fulcrum of the bell-crank lever abutting the wall of the passageway for rocking and sliding or rolling movement thereon; and spring means acting on the other arm of the bell-crank lever to bias the bell-crank lever into one position, the arrangement being such that application of a preset torque to the said one end of the first lever causes the first lever to rotate and pivot the bell-crank lever out of its one position against the action of the spring means, and thus causes part of the bell-crank lever, or a striker connected thereto, to strike the wall of the passageway to give an audible indication that the preset torque has been reached.

TORQUE SPANNERS

The invention relates to torque spanners. The invention provides a torque spanner which is adapted to give an audible indication that the preset torque has been reached.

It is preferred that the spring means are arrangeable to apply a preset load to the bell-crank lever, the bell-crank lever transmitting load to the first lever, the first lever, when the torque applied at the said one end is zero, being prevented from moving under the action of the load by a reaction between the first lever and the wall of the passageway so that torque applied to the first lever does not rotate the first lever away from the wall of the passageway to pivot the bell-crank lever until the applied torque imparts to the first lever a moment about its pivot greater than the moment imparted by the said reaction.

It is further preferred that the positions of the bell-crank lever and spring means are such that as the first lever begins to move the load transmitted to the first lever by the bell-crank lever reduces so that the first lever accelerates.

Preferably the spring means act on the said other arm of the bell-crank lever via a compression link pivotally connected to the said other arm. The spring means may comprise a plunger pivotally connected to the link and slidable (e.g. by means of its material properties or on rollers or balls) within the passageway and a coil spring on the side of the plunger remote from the levers one end of the spring acting against the plunger and the other end acting against an abutment on the body.

It is preferred that the link is arranged such that when the bell-crank lever is in the said one position the link extends along the passageway and is inclined to the axis of the passageway, and when the bell-crank lever pivots out of its said one position the link is caused to pivot into a position in which it lies substantially parallel to the axis of the passageway.

The link may be provided with a projection to serve as the striker.

Preferably the abutment on the body is movable along the passageway so that the compression of the spring may be varied to adjust the preset torque.

The fulcrum of the bell-crank lever may be provided with a roller.

Preferably the spanner automatically resets when the spanner is relieved of torque greater than or equal to the preset torque.

By way of example, a specific embodiment of the invention will now be described with reference to the accompanying drawings, in which:

FIG. 1 is a section through a torque spanner according to the invention under no load;

FIG. 2 is a part section through the torque spanner of FIG. 1 the pre-set torque having been applied;

FIG. 3 is a side section of the torque spanner of FIG. 1; and

FIG. 4 is a section through an alternative spanner head.

The spanner comprises a tubular body 10, a first lever 11 pivoted to the tube 10 at 12, a bell-crank lever 13 pivoted to lever 11 at 14, a link 15 pivoted to the bell-crank lever at 16, a plunger 17 pivoted to the link 15 at 18, an end cap 19, an adjusting screw 7, an adjusting nut 9, and a compression spring 20 lying between plunger 17 and adjusting nut 9.

The lever 11 carries in a socket at one end a square 21 which extends in a direction parallel to the axis of pivot 12. The square has two ball catches 22 and is arranged to receive any one of a number of torque applying heads such as wrench sockets.

The bell-crank lever 13 has at its fulcrum a roller 23 abutting the internal wall of tube 10. Thus the lever 13 pivots about its fulcrum by rocking on the tube wall.

The link 15 has an obliquely projecting end 24 to serve as a striker.

As best seen in FIG. 3 adjusting nut 9 is screwed onto the adjusting screw 7, and the action of spring 20 tends to urge the nut and screw to the right of the Figure. A circlip 8 engaging a groove in the internal wall of tube 10 holds the screw 7 in position. A cylindrical socket in one end of screw 7 engages a cylindrical extension of plunger 17 for centring purposes. The other end of screw 7 has a square section projection 6 which engages a square socket in cap 19. The cap 19 is fixed to the screw 7 by a flat-head screw, and nut 9 is keyed to the tube 10 to prevent the nut from rotating. Thus the screw is rotatable with the cap 19 and rotation of the cap 19 therefore causes nut 9 to move along tube 10, thus varying the degree of compression in spring 20.

In use the spanner parts are arranged in the stable state shown in FIG. 1. The spring 20 acting on plunger 17 holds the parts in position. A desired torque is set by adjusting cap 19 to apply a suitable compression to the spring. A pointer associated with the adjusting nut 9 indicates on a scale the torque which corresponds to any given position of the cap.

Once the desired torque has been set, the spanner may be used to apply torque to, for example, nuts, bolts, bottle caps, valves, plastic components etc. As torque is applied, an equal and opposite torque is applied to the lever 10. When the torque reaches the preset value lever 11 pivots anti-clockwise as viewed in FIGS. 1 and 2, lever 13 pivots clockwise, rolling slightly to the right along the tube, and link 15 urges the plunger and spring to the right, the parts taking up the position shown in FIG. 2. Link 15 operates with a toggle action and moves with increasing acceleration until projection 24 strikes the tube wall bringing the parts to rest and indicating audibly that the preset torque has been applied. In this position application of further force will cause the spanner to act as a conventional spanner.

Link 15 is of such dimensions that in the position shown in FIG. 2 pivot 16 lies below a line joining pivot 18 and fulcrum 23. Thus when the spanner is relieved of torque the spring 20 causes the parts to return to the position shown in FIG. 1. Thus the spanner automatically resets.

Furthermore the relative dimensions of the levers 11, 13 and the link 15, and the positioning of the pivots, provide a high mechanical advantage in favor of the spring. This means that a relatively weak spring may be used even with a spanner required to transmit relatively high torque. A secondary effect is that when the spring yields and the parts move after application of the preset torque the movement of the lever 11 is considerably less than that of link 15. Thus the amount of rotational movement of the spanner between application of the preset torque and the spanner reaching the position shown in FIG. 2 is very small. Consequently the spanner cannot pick up much speed after application of the preset torque before it begins to act as a conventional

spanner. This reduces the possibility that substantial additional torque will be accidentally applied in addition to the preset torque when the spring yields.

FIG. 4 shows an alternative head with which lever 11 may be provided. Instead of a square 21 carried in a square hole the head comprises a ratchet mounted square 28. The square has a ball-catch 29 for the attachment of torque applying means.

I claim:

1. A torque spanner comprising: a body having a tubular passageway therethrough; a first lever pivoted within the passageway intermediate its ends, one of its ends projecting from the passageway which end is arranged to apply torque or carry torque applying means of which the torque reaction tends to rotate the lever about its pivot; a bell-crank lever within the passageway, one arm of the bell-crank lever being pivotally connected to the other end of the first lever, the fulcrum of the bell-crank lever abutting the wall of the passageway for rocking and sliding movement thereon; a striker connected to the bell-crank lever; and spring means acting on the other arm of the bell-crank lever to bias the bell-crank lever into one position, the arrangement being such that application of a preset torque to the said one end of the first lever causes the first lever to rotate and pivot the bell-crank lever out of its one position against the action of the spring means, and thus cause the striker to strike the wall of the passageway to give an audible indication that the preset torque has been reached.

2. A torque spanner as claimed in claim 1 in which the spring means are arrangeable to apply a preset load to the bell-crank lever, the bell-crank lever transmitting load to the first lever, the first lever, when the torque applied at the said one end is zero, being prevented

from moving under the action of the load by a reaction between the first lever and the wall of the passageway so that torque applied to the first lever does not rotate the first lever away from the wall of the passageway to pivot the bell-crank lever until the applied torque imparts to the first lever a moment about its pivot greater than the moment imparted by the said reaction.

3. A torque spanner as claimed in claim 2 in which the positions of the bell-crank lever and spring means are such that as the first lever begins to move the load transmitted to the first lever by the bell-crank lever reduces so that the first lever accelerates.

4. A torque spanner as claimed in claim 1 in which the spring means act on the said other arm of the bell-crank lever via a compression link pivotally connected to the said other arm.

5. A torque spanner as claimed in claim 4 in which the spring means comprise a plunger pivotably connected to the link and slidable within the passageway and a coil spring on the side of the plunger remote from the levers one end of the spring acting against the plunger and the other end acting against an abutment on the body.

6. A torque spanner as claimed in claim 4 in which the link is arranged such that when the bell-crank lever is in the said one position the link extends along the passageway and is inclined to the axis of the passageway, and when the bell-crank lever pivots out of its said one position the link is caused to pivot into a position in which it lies substantially parallel to the axis of the passageway.

7. A torque spanner as claimed in claim 4 in which the link is provided with a projection to serve as the striker.
